Primary Examiner — Kendra Leslie Hamilton(74) Attorney, Agent, or Firm — Donald J. Ersler(57) CLAIM

The ornamental design for a pacifier, as shown and described.

DESCRIPTION

FIG. 1 is a top perspective view of a pacifier incorporating my new design;

FIG. 2 is a bottom perspective view thereof;

FIG. 3 is a bottom side perspective view thereof;

FIG. 4 is a top plan view thereof;

FIG. 5 is a bottom plan view thereof;

FIG. 6 is a left side or right side view thereof;

FIG. 7 is a front view thereof; and,

FIG. 8 is a rear view thereof.

The broken lines illustrate portions of the pacifier that form no part of the claimed design.
